PULL-OVER SHAFT DRIVE FOR AXMINSTER LOOMS

Victor F. Sepavich, Worcester, Mass., assignor to
Crompton & Knowles Loom Works, Worcester,
Mass., a corporation of Massachusetts

Application January 19, 1946, Serial No. 642,294

17 Claims. (Cl. 139—7)

1

This invention relates to improvements in Axminster looms and it is the general object of the invention to provide improved means for operating the pullover shaft by which the tube frames are moved one by one to transfer position.

Axminster looms ordinarily operate with a tube frame conveyor system which is advanced in part at least by a pullover shaft operated by a pawl and ratchet mechanism. Because of the nature of the pawl and ratchet mechanism it has been necessary in the past to employ very strong brakes which of themselves impose a considerable load on the moving means for the conveyor system.

It is an important object of my present invention to eliminate the pawl and ratchet feed mechanism for the pullover shaft and in its place substitute motor driven mechanism geared to the shaft. The motor is caused to operate during that part of the cycle of the loom in which the pullover shaft is moved angularly, after which the motor serves as a lock to hold the pullover shaft stationary. The motor alternately turns the pullover shaft and then locks it electromagnetically. This result I accomplish by using a motor having a wound rotor the windings of which are connected together when the shaft is to be turned, and are then connected directly to the power lines which feed the stator when the shaft is to be locked.

In addition to the motor drive for the shaft I may also use a second motor for the conveyor system and control it simultaneously with and in the same manner as the shaft motor is controlled.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a partial side elevation of an Axminster loom having my invention applied thereto,

Fig. 2 is a detailed front elevation looking in the direction of arrow 2, Fig. 1,

Fig. 3 is an enlarged front elevation looking in the direction of arrow 3, Fig. 1, showing the switching mechanism for the motor,

Fig. 4 is a detailed vertical section on line 4—4 of Fig. 3,

Fig. 5 is a side elevation looking in the direction of arrow 5, Fig. 3, parts being in section,

Fig. 6 is a vertical section on line 6—6 of Fig. 5, and

Fig. 7 is a diagrammatic view showing the motor controlling circuits.

Referring particularly to Fig. 1, the frame of the loom is indicated at 10 and the front and back tuft cutter knives at 11 and 12, respectively.

2

The fabric F leads forwardly from the warp threads W which define the shed for the weft needle N. The tube frame conveyor system designated generally at C is supported by an overhead structure including horizontal runs 15 and 16 on which are mounted sprockets 17 around which extend the endless tube frame transporting chains 18 and 19. Tube frames 20 extend between the chains and are provided in the usual manner with spools 21 to supply the tuft yarn 22.

At each side of the loom there is located a transerrer arm for detaching the tube frames one at a time from the chains and moving them toward cloth forming position. In Fig. 1 the right hand transfer arm is indicated at 25 and a rocking rod 26 is provided to give the tube frame its usual rolling-in motions. Rod 26 is operated by a lever 27 and link 28 connected to a lever 29 positioned for cooperation with a cam 30 on the loom shaft 31. Rising and falling movements of the transfer arm are effected by rod 32, lever 33 and a second cam 34 on shaft 31. The lay L and weft needle N have operative movements every beat or pick of the loom.

In operation of the loom, and assuming that three-shot Axminster fabric is being woven, the bottom shaft 31 will rotate once every third beat of the lay L, and the needle N will be inserted into the warp shed each beat or pick of the loom. During the tuft forming operation the transfer arms will detach the tube frame in transfer position from the chain, move it down to cloth forming position, roll the tube frame, and then lift the frame a slight distance to pull off yarn for the next tuft forming operation. The cutter blades 11 and 12 then sever the tufts from the tube frame and the transerrer arms thereafter move upwardly to return the tube frame to the chain. This tuft forming operation will occur every third pick of the loom, and when it is completed the transporting conveyor system will advance to move the next tube frame to transfer position.

Advance movement of the chains is effected by means of a pullover shaft 40 which is journaled for rotation in stands secured to the upper part of the loom frame and one of which is shown at 41. Each end of the pullover shaft has secured thereto a sprocket wheel similar to that shown at 42 in Fig. 1 for moving the conveyor chains.

Except for certain features of the pullover shaft pointed out hereinafter the matter thus far described is constructed and operated in the usual manner.

In carrying my present invention into effect I provide separate motor means for rocking the pullover shaft 40 prior to a tuft forming operation and then holding it or locking it electromagnetically in stationary position during the

tufting operation. Accordingly, a motor M of the wound rotor alternating current type having three windings a, b and c is mounted on a bracket 45 secured to the loom frame and has a pinion 46 meshing with a gear 47 rotatable on a stationary stud 48 supported by the bracket 45. A second pinion 49 fast with gear 47 meshes with a second gear 50 which is secured to the pullover shaft 49. The reduction gearing between the motor and shaft 40 is such that a given number of rotations of the motor produces the required angular motion of the shaft to move a new tube frame to transfer position.

The shaft 31 has secured thereto the switching devices for controlling the motor M. These switch devices are designated at I, II and III and since they are alike only one of them will be described in detail.

A disk 60 of electric current conducting material is secured to a bushing 61 made of insulating material and pinned as at 62 to the shaft 31 so that the disk 60 is insulated from the shaft. The disk has molded therein or otherwise secured thereto an arcuate peripheral plate 65 of electric insulating material to which is secured an electric current conducting contact strip 66 concentric with the peripheral surface 67 of the disk. The contact strip 66 is therefore insulated from the disk but is secured to it and turns with it.

Disposed laterally on the disk 60 is a resistor element 79 mounted on an insulating arcuate base 74 secured to the disk 60 as at 72. A contact arm 73 is positioned for engagement with the resistor and is held in adjusted angular position on and in electric contact with the shaft 31 by a clamping set screw 75. The resistor 79 is electrically connected to contact strip 66 by wire or conductor 76 so that brush 81 is connected through part of the resistor to shaft 31 whenever the brush engages contact 66.

Extending parallel to the shaft 31 is a rod 80 held in fixed position on the loom and supporting a brush 81 for engagement with the periphery 67 of the disk 60 and the contact strip 66. An insulated holder 82 for the brush is secured to rod 80 and keeps the latter out of electric connection with the brush. The brushes 81 of the units I, II and III are connected by wires 85, 86 and 87 to the three windings a, b and c, respectively, of the rotor R of the motor M.

Each unit includes a holder 90 clamped to rod 80 by a screw 91 and provided with a shank 92 made of insulating material and holding a support 93 for a brush 94 which is in continuous electric contact with the left side of disk 60, see Figs. 3 and 6. The brushes 94 of the units I, II and III are connected by wires 95, 96 and 97 respectively to the main power lines 101, 102 and 103 which supply three phase alternating electric current.

Referring to Fig. 7 and assuming that the loom has reached a position where it is necessary to start an angular movement of the pullover shaft, shaft 31 will have turned to a position such that brushes 81 will contact the strips 66. Winding a will then be connected by wire 85 and its brush 81 through that part of the corresponding resistor 79 between conductor 76 and arm 73 to shaft 31. Similarly, windings b and c will also be connected to shaft 31, and since all the windings are thus connected together the rotor will turn. The rate of turning will be determined by the amount of resistors 79 in circuit with their wind-

ings, and this in turn is determined by the position of arms 73.

Under these conditions the rotor will turn so long as the shaft 31 is in position to keep brushes 81 in contact with strips 66, and motor M will act through its reduction gearing to turn the pullover shaft. Contact strip 66 is of such length that the pullover shaft will be turned the proper amount to advance the next tube frame to transfer position.

As the shafts 31 and 40 turn together the brushes 81 will eventually leave the contacts 66 and the windings are no longer connected to each other through shaft 31. Brushes 81 will then engage the periphery of the disks 60, whereupon the windings of the rotor will be connected through their wires 85, 86 and 87 to the disks 60 and brushes 94 to power wires 101, 102 and 103. Under this condition the windings a, b and c are connected directly across the same feed wires which supply the rotating field of the stator, and the rotor will be magnetically locked in a stationary position. This locking continues until brushes 81 again engage contacts 66. The transfer arms operate during this period of locking and assurance is given that the tube frame will be properly returned to its chains after the tufting operation.

The speed of the rotor will be determined by the amount of resistance which is in series with its winding and in order that this speed may be accurately adjusted the contact arms 73 are made angularly adjustable as already described. The gear reduction between the motor M and the pullover shaft is so proportioned and related to the rate of turning of the motor that the period of contact between the brushes 81 and the contact strip 66 will be just sufficient to cause the aforesaid given number of revolutions of the motor and give the pullover shaft its requisite amount of angular movement to move the next tube frame into transfer position.

As already mentioned, the conveyor system C can if desired be driven by a motor additional to that provided for the pullover shaft. Such a motor is shown at M' in Fig. 1 together with appropriate gearing for driving the chains 18 and 19. The motor M' is similar to motor M and is mounted on a stand 110 forming part of the overhead mechanism 15 and has a pinion 111 meshing with a gear 112 rotatable on a bearing 113. A second pinion 114 rotating with gear 112 meshes with a gear 115 secured to a shaft 116 rotating in bearings 117 on the structure 15. Sprockets 118 similar to sprockets 42 are secured to shaft 116 and advance the chains when motor M' runs. The gear reductions are the same in each case, so that whenever motors M and M' run simultaneously the chains will be fed continuously by power supplied to them at two spaced points.

In Fig. 7 the rotor R' of the motor M' is provided with windings a', b' and c' which are connected by wires 120, 121 and 122 to wires 85, 86 and 87, respectively. By these connections the rotors of the two motors are always in the same condition so that when the pullover shaft is being moved by motor M, the motor M' will advance its part of the conveyor system, and when the rotor of motor M is magnetically locked there will be a similar locking of the rotor R'. Conduits 125 and 126 are provided to hold wires connecting the motors with the switching units. I wish it to be understood, however, that I am not restricted in the practice of my invention to the

use of the second motor M' , nor am I to be limited to the particular showing of the overhead mechanism as set forth in Fig. 1.

From the foregoing it will be seen that I have provided an electric motor connected to the pull-over shaft of an Axminster loom and controlled in such manner that the motor alternately turns and electromagnetically locks the pullover shaft. This result is obtained by using a wound rotor and connecting its windings together preferably through speed regulating resistance means to cause turning of the rotor when the pullover shaft is to be turned, and then connecting the windings directly to the same line which feeds the stator of the motor so that the rotor is electromagnetically locked against turning. Any slight angular shift between the rotor and the stator during the locking period will be greatly minimized by the reduction gearing between the motor, and the pullover shaft and the conveyor chains will be held in correct position for registry with the tube frames when the latter are returned to the chains subsequent to a tuft forming operation. Also, an additional motor M' similar to motor M may be used to drive the chains at points spaced from the pullover shaft. I do not claim the broad feature of two motors to drive the conveyor system except as these motors alternately move and electromagnetically lock the system.

Having thus described my invention it will be seen that changes and modifications may be made therein by those skilled in the art without departing from the spirit and scope of the invention and I do not wish to be limited to the details herein disclosed, but what I claim is:

1. In an Axminster loom having a tube frame transporting system part of which has periods of activity for advancing tube frames alternating with periods of inactivity during which the tube frames are detached one at a time from the system, a part moving in timed relation with the loom, an electric motor operatively connected to said part of the transporting system, and electric control means for the motor operated by said second named part and causing said motor to run to cause said system to have said periods of activity and causing said motor to stop to cause said system to have said periods of inactivity.

2. In an Axminster loom having a tube frame transporting system part of which has periods of activity for advancing tube frames alternating with periods of inactivity during which the tube frames are detached one at a time from the system, an electric motor operatively connected to said part of said system and constructed to be capable of running or being electromagnetically locked against motion, and control means causing said motor to run to cause said system to have said periods of activity and causing said motor to be electromagnetically locked against motion during said periods of inactivity.

3. In an Axminster loom having a tube frame transporting system part of which has periods of activity for advancing tube frames alternating with periods of inactivity during which the tube frames are detached one at a time from the system, an alternating current motor having a stator and a rotor provided with windings and operatively connected to said part of the system, and electric control means for said windings effective to cause the rotor to turn to cause said system to have said periods of activity and effective during said periods of inactivity to cause said windings to cooperate with the stator and

constitute an electromagnetic lock preventing motion of said rotor and said part of said system.

4. In an Axminster loom having a tube frame transporting system part of which has periods of activity for advancing tube frames alternating with periods of inactivity during which the tube frames are detached one at a time from the system, a multiphase alternating current electric motor having a rotor capable of turning and also capable of being electromagnetically locked against turning, and control means for said motor causing said rotor to turn to cause said part of the system to have periods of activity and causing said rotor to be electromagnetically locked during said periods of inactivity.

5. In an Axminster loom having a tube frame transporting system part of which has periods of activity for advancing tube frames alternating with periods of inactivity during which the tube frames are detached one at a time from the system for a tuft forming operation, a pull-over shaft geared to said system, an electric motor operatively connected to the shaft in such manner that the shaft and motor turn together and are at rest together, said motor capable of being electromagnetically locked against turning to hold said shaft stationary, and control means for the motor causing the latter to run to cause said part of the system to have said periods of activity and causing said motor to be electromagnetically locked during said periods of inactivity.

6. In an Axminster loom having a tube frame transporting system part of which has periods of activity for advancing tube frames alternating with periods of inactivity during which the tube frames are detached one at a time from the system for a tuft forming operation, a pullover shaft for said system to be turned during said periods of activity and to be held at rest during said periods of inactivity, an electric motor geared to said shaft and capable of running and also capable of being electromagnetically locked, and control means for the motor causing the latter to run to turn said shaft during said periods of activity and effective to lock said motor electromagnetically against turning during said periods of inactivity to prevent turning of the shaft.

7. In an Axminster loom having a tube frame transporting system part of which has periods of motion for advancing tube frames alternating with periods of rest during which the tube frames are detached one at a time from the system for a tuft forming operation, a multiphase electric motor provided with a stator connected to a source of multiphase electric power, a rotor for the motor having windings and operatively connected to said system, and control means for said windings effective during said periods of motion to connect said windings together to cause turning of the rotor and effective during said periods of rest to connect said windings to said source of multiphase electric power and cause the rotor to be electromagnetically locked against turning.

8. In an Axminster loom having a tube frame transporting system having periods of motion alternating with periods of rest, a multiphase electric motor having a stator connected to a multiphase source of electric power, a rotor for the motor operatively connected to said system and having windings, and control means for said windings to connect the latter together to cause turning of the rotor for periods corre-

sponding to said periods of motion and also effective to connect said windings to said source of multiphase electric power for periods corresponding to said periods of rest to lock said rotor electromagnetically and prevent movement of said system.

9. In an Axminster loom having a tube frame transporting system having alternating periods of motion and rest, a multiphase alternating current electric motor operatively connected to the said system in such manner as to be required to turn during said periods of motion and being required to be at rest during said periods of rest, said motor being so constructed that it can be caused either to run or be electromagnetically locked against running, and control means for said motor causing the latter to run to effect said periods of motion of the system and also cause said motor to be electromagnetically locked against motion to effect said periods of rest of said system.

10. In an Axminster loom operating with a pullover shaft to move tube frames one at a time to transfer position, unitary means operatively connected to said shaft in such manner as to be capable of alternately moving and locking said shaft, said unitary means comprising an electric motor capable in one condition of running and capable in another condition of being electromagnetically locked, and means controlling the motor and causing the latter to be under said conditions alternately.

11. In an Axminster loom having a pullover shaft to move tube frames one at a time to transfer position, unitary means for alternately moving and locking said shaft including an electric motor capable of running in one condition and capable of being electromagnetically locked against motion in another condition, driving gearing between the motor and the shaft causing the latter to move when the motor runs and be locked against motion when the motor is electromagnetically locked, and electric control means for the motor operative during loom operation to cause said motor to be first under one of said conditions and then under the other of said conditions.

12. In an Axminster loom having a pullover shaft to move tube frames one at a time to transfer position, transfer means to move a tube frame away from the shaft and then return the tube frame to transfer position during a tuft forming interval, an electric motor operatively connected to said shaft and capable of being under two conditions in one of which said motor runs to turn the shaft and in the other condition of which the motor is electromagnetically locked to prevent turning of the shaft, and electric control means for the motor causing the latter to be under said one condition between said tuft forming intervals and be under said other condition during said tuft forming condition.

13. In an Axminster loom having a pullover shaft to move tube frames one at a time to transfer position, transfer means operative during a tuft forming interval of loom operation to move a tube frame away from transfer position to tuft forming position and then return the tube frame to transfer position, unitary means for alternately turning said shaft and locking said shaft against turning and including an electric motor

operative under one condition to run and cause said shaft to turn and operative under another condition to be electromagnetically locked to prevent turning of the shaft, and electric control means for said motor effective between successive tuft forming intervals during loom operation to cause said motor to be under said one condition and effective during said interval to cause said motor to be under the other of said conditions to prevent movement of the shaft during tuft forming intervals.

14. In an Axminster loom having a pullover shaft to move tube frames one at a time to transfer position, said shaft requiring a given angular movement to move a tube frame adjacent to transfer position into transfer position, an electric motor operative alternately to turn and stop turning of said shaft, resistance means connected to said motor when the latter is turning said shaft, and means to vary said resistance means to cause an amount of turning of said motor which will produce said given angular movement of the shaft.

15. In an Axminster loom having an operating shaft which turns continuously during loom operation and having a pullover shaft to have intermittent periods of angular motion to move tube frames one at a time to transfer position, an electric motor operatively connected to the pullover shaft, and control means moved by the operating shaft and causing said motor to have intermittent periods of operation to cause said pullover shaft to have said intermittent periods of angular movement.

16. In an Axminster loom having an operating shaft which runs continuously during loom operation and having a pullover shaft having intermittent periods of angular movement to move tube frames one at a time to transfer position, an electric motor operatively connected to the pullover shaft to cause angular movement of the latter when the motor is running, and control means for said motor moving with the operating shaft and effective to cause the motor to run for a given part of a rotation of the operating shaft corresponding to a period of angular movement of said pullover shaft and effective to prevent turning of the motor for the remainder of said rotation of the operating shaft.

17. In an Axminster loom having an operating shaft which completes a rotation in a cycle comprising a plurality of beats of the loom and including a tuft forming period, a pullover shaft to move tube frames one at a time to transfer position between tuft forming periods, unitary means including a motor operative to turn said pullover shaft when the motor is under one condition, said motor when under another condition being electromagnetically locked to prevent turning of the pullover shaft, and control means moving with the operating shaft and effective during a part of a rotation of the latter to cause said motor to be under said one condition between tuft forming periods, and effective during the remainder of the rotation of said operating shaft to cause said motor to be under the other of said conditions during a tuft forming operation to enable the electromagnetically locked motor to prevent movement of the pullover shaft when a tube frame is in transfer position.

VICTOR F. SEPovich.
